United States Patent

Des. 239,790
Patented May 11, 1976

239,790

DENTAL CHAIR

Ronald C. Webb, Red Lion, Pa., assignor to Dentsply
Research & Development Corp., Milford, Del.

Filed Dec. 17, 1974, Ser. No. 533,733

Term of patent 14 years

Int. Cl. D6—01

U.S. Cl. D6—22

FIG. 1

FIG. 2

FIG. 4

FIG. 3

FIG. 1 is a side elevation of a dental chair embodying my design.

FIG. 2 is a top plan view thereof.

FIG. 3 is a rear elevation thereof.

FIG. 4 is a front elevation thereof.

The side of the chair opposite that shown in FIG. 1 is a mirror image of that shown in FIG. 1.

I claim:

The ornamental design for a dental chair, as shown and described.
